UNITED STATES PATENT OFFICE.

STANLEY M. MCINTYRE, OF CINCINNATI, OHIO.

CORNER PIECE FOR MILK CRATES AND THE LIKE.

Application filed January 20, 1923. Serial No. 614,003.

To all whom it may concern:

Be it known that I, STANLEY M. MCINTYRE, a citizen of the United States of America, and a resident of Cincinnati, in the county of Hamilton and State of Ohio, have invented a new and useful Improvement in a Corner Piece for Milk Crates and the like, of which the following is a specification.

10 An object of my invention is to provide a milk crate structure that is simple, strong and efficient.

Another object of my invention is to provide a device for the purposes stated that 15 may be formed integral thereby reducing the effort and labor required to produce milk crates and the like.

Another object of my invention is to eliminate certain objectionable features 20 heretofore encountered in milk crates and the like.

These and other objects are attained by the means described herein and disclosed in the accompanying drawings, in which—

25 Fig. 1 is a perspective view of a milk crate embodying my invention.

Fig. 2 is an enlarged perspective view of a corner piece embodying my invention.

Fig. 3 is an enlarged fragmental view of 30 a crate having mounted on it a corner piece embodying my invention showing the inside structure of the crate and the corner piece.

Fig. 4 is a sectional view on a reduced 35 scale on line 4—4 of Fig. 3.

Fig. 5 is a development of a corner piece embodying my invention.

Referring to Fig. 5, the corner piece of 40 my invention comprises a flat band of metal adapted to be cut to the form disclosed and adapted to be bent upon the dotted lines. The corner piece comprises an outer section 6 consisting of flaps 7 and 8 bent along line 9 at an angle of substantially 90 degrees.

45 At the upper and lower ends of flaps 7 and 8, said flaps are bent upon lines 10 and 11 to form upper ledges 12 and 120 and lower ledges 13 and 130, the adjacent edges 14, 15, 16 and 17 of which are adapted to lie im-

50 mediately adjacent one another, in fact to engage upon one another when the flaps 7 and 8 are disposed at the angle stated. The ledges 12 and 120 carry upper inside flaps 18 and 19 and are adapted to be bent upon the lines 20 and 21 so as to lie upon the inner faces 22 and 23 of the upper slats 24 and 25

of the crate 26. The lower ledge 130 carries a lower inside flap 27 adapted to extend about the lower edge 28 and to lie upon the inner face 29 of the lower slat 30 of the 60 crate. The ledge 13 carries an inside lap 31 adapted to extend upwardly inside the crate and to project beyond the upper edges of the slats 24 and 25. The lap 31 carries a lap 32 that is bent upon the lap 31 upon line 33 so as to dispose the lap 31 in substantial parallelism with the flap 7 and to dispose the lap 32 in substantial parallelism with the flap 8 when the corner piece is mounted upon the crate. The several laps 70 and flaps are provided with registering perforations 34 through which suitable fastening means such as bolts 35 may be inserted for securing the slats of the crates and the corner pieces upon one another, and for securing the parts of the corner strip in the position shown in Fig. 2. Suitable wires 350 are laced between the slats to provide a bottom for the crate as is common in the art. 80

What I claim is:

1. A corner piece of the class described comprising a flap and a lap extending in substantial parallelism, a bottom ledge spacing the lap and the flap at one end, an upper inside flap extending in substantial parallelism with the lap, an upper ledge spacing the inside flap and the flap and disposing the inside flap adjacent the flap, a second flap carried by the first flap and extending longitudinally of the first flap, the second flap having an upper and a lower ledge disposed at its opposite ends, an upper inside flap carried by the upper ledge and a lower inside flap carried by the lower ledge, the ledges spacedly supporting the two last mentioned inside flaps in substantial parallelism with the flap, and a second lap carried by the first lap extending at an angle to the first lap, and in substantial parallelism with the second mentioned flap. 95

2. A corner piece of the class described comprising a flap and a lap extending in substantial parallelism, a bottom ledge spacing the lap and the flap at one end, an upper inside flap extending in substantial parallelism with the lap, an upper ledge spacing the inside flap and the flap and disposing the inside flap adjacent the lap, a second flap carried by the first flap and extending longitudinally of the first flap, the second flap having an upper and a lower 105 110

ledge disposed at its opposite ends, an upper inside flap carried by the upper ledge and a lower inside flap carried by the lower ledge, the ledges spacedly supporting the 5 two last mentioned inside flaps in substantial parallelism with the flap, a second lap carried by the first lap extending at an angle to the first lap, and in substantial parallelism with the second mentioned flap, and 10 means for securing the parts in position and for mounting the device at the corner of crates and the like.

3. In a crate the combination with slats disposed at an angle one to the other, of 15 corner pieces for mounting at the ends of the slats, the corner pieces extending from a point inside the crate upwardly and over the upper edge of the crate, thence downwardly over the outer sides of the slats, 20 thence over the bottom edges of the crate, thence upwardly inside the crate over, beyond and adjacent the first mentioned portions of said corner pieces, and means extending through the slats and through the 25 corner pieces for securing the slats and corner pieces upon one another.

4. In a crate the combination with slats disposed at an angle one to the other, of corner pieces for mounting at the ends of 30 the slats, the corner pieces extending from a point inside the crate upwardly and over the upper edge of the crate, thence downwardly over the outer sides of the slats, thence over the bottom edges of the crate, 35 thence upwardly inside the crate over and adjacent the first mentioned portions of said corner pieces, and projecting upwardly be-

yond the upper edge of the crate, and means extending through the slats and through the corner pieces for securing the slats and corner pieces upon one another. 40

5. In a crate the combination with slats disposed at an angle one to the other, of corner pieces for mounting at the ends of the slats, the corner pieces comprising a pair 45 of flaps bent at an angle to one another along a line extending longitudinally of said flaps, a lower ledge carried by each of the flaps, said ledges being separate one from the other, and being bent upon the flaps for 50 bringing the opposed edges of the ledges immediately adjacent, a lower inside flap carried by one ledge and bent at an angle to said ledge for disposing said lower inside flap in substantial parallelism with the flap carrying said ledge, a pair of inside laps carried by the second ledge, one of said inside laps being offset from the second mentioned ledge, the inside laps being bent upon one another upon a line extending longitudinally of said laps and at an angle substantially identical to the angle at which the flaps are bent on one another, the second inside lap being bent upon the second mentioned ledge for disposing the second inside 55 lap in substantial parallelism with one of the flaps and for disposing the first mentioned inside lap in substantial parallelism with the lower inside flap and with the flap carrying said lower inside flap. 60

In testimony whereof, I have hereunto subscribed my name this 16th day of January, 1923.

STANLEY M. McINTYRE.
